(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface showing our new design; and, FIG. 2 is a front view of a display screen or portion thereof with graphical user interface showing our new design.

The broken lines around the Figures show a display screen or portion thereof and form no part of the claimed design. The broken lines within the Figures show unclaimed portions of the graphical user interface and form no part of the claimed design. The dot-dash lines within the Figures and the area between the dot-dash lines and the broken lines show environment that forms no part of the claimed design.
